GEAR ROLLING MACHINE

Herman Finzel, Chicago, Ill., assignor to N. H. Well, Ralph Well, and George Well, all of Chicago, Ill., as trustees

Application December 15, 1944, Serial No. 568,321

12 Claims. (Cl. 80—16)

1

The present invention relates to a method of and apparatus for rolling gears.

Heretofore gear rolling machines have been proposed in which a preheated blank is put into the machine and a die roll is fed towards the blank to sink the teeth into the blank. It has also been proposed to oscillate the die roll and the blank during the rolling process, so as to insure symmetrical teeth and to rotate the blank and the die roll continuously in the same direction after the teeth are formed, so as to planish the teeth and produce thereon a tough smooth surface.

In the machines proposed heretofore the power for clamping the blank in the machine, for feeding the die roll into the blank and for rotating the die roll and the blank, was supplied by a single driving motor, the different motions being obtained by means of cams, toggles, reversing gears, clutches and belts, connected between the driving motor and the various power driven elements of the machine.

However, gears of different size or of different materials require different rates of feed of the die roll towards the blank relative to the speed of rotation of the die roll and blank, but with a single driving motor for the entire machine such different ratios are only attainable by complicated speed change devices requiring a multiplicity of gears in the power trains between the single driving motor and the various driven parts of the machine. This is objectionable because the unavoidable back lash affects the accuracy of the work, nor permit such speed gears to vary the speed of one element relative to the other in a continuous manner during the operating cycle of the machine.

An object of the present invention is to avoid the aforementioned disadvantages.

A further object is the addition of novel and advantageous features by providing for an independent motor drive for each of the principal functions of the machine, and independent adjustment, if necessary, of the speed of these motors during the operating cycle. By providing independent motors for each of the main motions of the machine the speeds of the different elements relative to each other may be varied independently during the operating cycle, which is a very desirable feature resulting in great economy in time, as will be pointed out hereinafter.

In the machines heretofore proposed, a preheated blank is put into the machine and is then rolled. To produce a highly finished gear by rolling at high temperature it is essential to cool the die roll during the rolling process, so as to

2

prevent formation of scale on the blank and its adhesion and building up on the die roll, which greatly impairs the accuracy and finish of the completed gear. As a result the blank is rapidly cooled, the power for rolling increased, and the finished gear is inaccurate as to dimensions and requires further finishing operations after it is removed from the machine.

10 A further object of the present invention is to provide for heating of the gear blank to the proper temperature and maintaining said temperature during the entire rolling process, while at the same time the die roll is cooled. The loss of heat from the blank to the die roll is compensated by the supply of heating energy during the rolling process.

Another object of the invention is to provide for automatic control of the various functions of the machine so that upon initiation of the 20 rolling cycle by the insertion of a blank it is completed in the desired manner without further interference of the operator.

The invention has the further object to provide for surrounding the blank during the rolling 25 process with a neutral atmosphere so as to prevent oxidation and scaling. If desired a gaseous carburizing or nitriting agent may be employed to treat the gears upon completion of the rolling and while the finished gear is still in the machine.

30 The invention further provides means to protect the various parts of the machine from the heat supplied to the blank, so as to avoid distortions in the machine during the rolling process, which may cause serious dimensional changes 35 and may lead to inaccuracy of the finished product.

As the rim of the gear blank is in a plastic 40 state during the rolling process it is necessary, particularly on small blanks where the temperature of the hub is nearly the same as that of the plastic circumference, to protect the hub from undue axial clamping pressure to prevent its deformation, and the present invention provides means for adjustment and limitation of the pressure to a desired value.

While the following description of the construction and operation of a machine embodying 45 the invention contemplates the rolling of gears at an elevated temperature of the gear material, it will be apparent that the machine may also be employed for rolling gears of materials which are plastic at normal temperature, such as certain bronzes. In such cases certain elements for heating and cooling may be omitted or their operation may be suspended.

Other features and advantages of the system

will appear from the following description and the accompanying drawings.

The accompanying drawings show an embodiment of the invention adapted for rolling spur gears, including certain modifications of which the machine is capable. In the drawing,

Fig. 1 is a horizontal section of a gear rolling machine along the lines 1—1 of Fig. 3.

Fig. 2 is a section of a part of the machine along the lines 2—2 of Fig. 1, to which is added a means 10 for heating the blank during rolling and for subsequent cooling thereof.

Fig. 3 is a vertical section through the machine along the line 3—3 of Fig. 1.

Fig. 4 is a vertical section along the lines 4—4 15 of Fig. 1.

Fig. 5 is an enlarged section of the holding and driving means for the blank shown in Figs. 1, 3 and 4.

Fig. 6 is a modification of the die shown in Fig. 1.

Figs. 7 and 8 comprise a diagram of the circuits and apparatus for the electric control of the machine shown in Figs. 1 to 5.

Referring to Figs. 1 to 6, inclusive, the same illustrate a machine having a compact rigid frame or bed plate 20, on which a shaft or spindle 21 is rotatably mounted on roller bearings 22 and 23. A second shaft 24 is rotatably mounted in axial alignment with the shaft 21 in bearings 25 and 26. These bearings in turn are mounted one near each end of a hollow piston 27, which is arranged for reciprocatory sliding engagement within a cylinder 28, forming a part of the frame 20. The cylinder 28 is provided with anti-friction rings or liners 29 and 30, for reducing the sliding friction between the cylinder 28 and the piston 27.

As shown in detail in Fig. 5, one end of the shaft 21 is provided with a central counter bore 31 to receive the reduced end of a generally annular jaw 32. The jaw 32 has a circular concentric bore 33, through which passes the shank of a headed pin 34, the head of which abuts the inner end surface of the jaw 32. Interposed between the head of the pin 34 and the bottom of the counterbore 31, is a spring 35, which urges said pin 34 outwardly, but which permits it to yield to a pressure tending to move it inwardly. The bore 33 may be enlarged at the outer face of the jaw 32 as shown at 36, to receive the hub of a gear blank.

The shaft 24 is provided with a jaw 37 which is similar to the jaw 32, except for differences in dimensions of the enlarged bore 36, to conform to the other end of the hub of the gear blank. The jaw 37 is also provided with a headed pin 38 similar to the pin 34, but the pin 38 is held rigid in the jaw 37 and is not arranged to slide longitudinally in response to an axial pressure thereon.

As best shown in Figs. 1 and 4, the shaft 21 is provided, at the end opposite to that on which the jaw 32 is mounted, with a bevel pinion 39, which engages a bevel gear 40, the latter being rotatably mounted in a pair of bearings 41 on the frame 20. The gear 40 is coupled to a splined shaft 42, the rearward extension of which is journaled in twin bearings 43 mounted on the frame 20. A spur gear 45 is fastened to the rear end of the shaft 42. The spur gear 45 meshes with a pinion 46 fastened to a horizontal shaft 47, which is journaled in the frame 20 by means of the bearings 48 and 49. The outer end of the shaft 47 is provided with a grooved pulley 50 which is

connected by multiple V-belts 51 with a pulley 52, of a reversible motor 53 for rotation of the shaft 47 in opposite directions. If desired a magnetic brake (not shown) which is energized for release upon energization of the motor 53 may be mounted on the shaft 47 or on the shaft of motor 53.

Rigidly supported in the frame 20 and parallel to the shaft 42 are one or more upper guide bars 54 and lower guide bars 55, for guiding a slide block 56, which slide block supports the shaft for the rotating tool of the machine. The slide block 56 is movable transversely to the axis of the shafts 21 and 24 in a horizontal direction.

Rotatably mounted on the slide block 56 in bearings 57 and 58 is a shaft 59 which carries the tool or die 60. The shaft 59 is provided with a bevel gear 61, which is adapted to engage a bevel gear 62. The beveled gear 62 is rotatably mounted by means of bearings 63 on the slide block 56 concentric with the shaft 42. The hub of the gear 62 is provided with a splined hole arranged for sliding engagement with the splined shaft 42. The slide block 56 may be driven forward at a slow rate of speed by a feed motor 64 and moved backward by a retracting motor 65. The arrangement being as follows: The block 56 is provided with a threaded bushing 66, having its central axis at right angles to and in the horizontal plane of the shafts 21 and 59, as best shown in Fig. 3. A screw 67 is threaded for engagement with said bushing 66. The outer end of the screw 67 is provided with thrust collars 68 and 69 and is supported from the frame 20 by a pair of thrust bearings 70, which engage the collars 68 and 69, to permit rotation of the screw 67 and to move the slide block 56 in one direction or the other, the thrust bearings opposing the horizontal thrusts due to such movement. The screw 40 67 is suitably coupled to a shaft 70, which shaft is in axial alignment with the screw and arranged to transmit its rotation to the screw. The shaft 70 is in turn supported by a sleeve 71, which latter is rotatably supported by bearings 72 and 73, on the frame 20. The sleeve 71 has keyed thereto a worm gear 74. A driving worm 75 is mounted on a shaft 76 in driving engagement with the worm gear 74. The shaft 76 also has fastened thereto a pulley 77 which is connected by means of V-belts 78, to a pulley 79, keyed to the shaft of the motor 64. Thus when the motor 64 rotates it causes rotation of the worm 75, worm gear 74, and sleeve 71.

Keyed to the sleeve 71 is a bevel gear 80, of a set of planetary gears 81. The bevel gear 80 is engaged by one or several planet gears 82 of said gear set 81. These planet gears are rotatably supported on stub shafts 83, which in turn are fastened to a casing 84 of the gear set 81, and to a hub 85 fastened to the shaft 70, the casing 84 in turn being rotatably supported by bearings 86. The gear set includes another gear 87 which is in engagement with the planet gears 82. The gear 87 is keyed to a shaft 88, which shaft is rotatably supported on the frame 20 by bearings 89. Also keyed to the shaft 88 is a belt pulley 90 which is connected by means of a V-belt 91 to a pulley 92 keyed to the shaft of the motor 65. The motor 65 is further provided with a brake 93, which brake is energized for release upon energization of the motor 65.

The arrangement as described thus far operates in the following manner: It is assumed that a suitable controller is provided for alternate energization of the motors 64 and 65. After

the main drive of the machine has been started, a workpiece *W* has been placed in the machine and the shafts *21* and *59* are rotating, the motor *64* is energized while the motor *65* remains de-energized. As the brake *93* prevents rotation of the armature of the motor *65*, the gear *87* remains stationary, while the gear *80* and with it the gears *82* rotate. This causes rotation of the casing *84* and with it of hub *85*, in a well known manner, thereby rotating the shaft *70* at a slow speed. This rotates the screw *67* to feed to the slide *56* towards the work. When the slide *56* has been moved to the desired extreme inward position the motor *64* may be deenergized by operation of the manual control referred to or the machine may be provided with a limit switch which, depending upon the position attained by the slide block *56* cuts off the motor *64* and brings the machine to rest. The operator may then manipulate the controller to energize the motor *65* and simultaneously release the brake *93*. This causes rotation of the gear *87* while the gear *80* stands still. The casing *84* will now rotate in the opposite direction thereby causing reverse rotation of the shaft *70* and of the screw *67* to retract the slide block *56* from the work. As the motor *65* is connected to the shaft *70* with a much higher transmission ratio than the transmission ratio between the motor *64* and the sleeve *71*, the return movement of the slide block *56* will be at a more rapid rate than the forward movement. It also should be pointed out that the motor *64* does not require a brake as the transmission ratio of the worm gear *74* and the worm *75* and the lead angle of the worm are such, that the reverse torque delivered to the sleeve *71*, through the planetary gear set does not overcome the static friction of the worm gear drive, so that the latter is self locking against reverse power torque.

It will of course be apparent that a limit switch may also be provided upon the slide block *56* for actuation in its extreme outward position, that is, the position shown in dotted lines in Figs. 1 and 3, in which position the motor *65* and the brake *93* will be deenergized to bring the slide block promptly to rest.

As shown in Fig. 1, the die roll *60* is a disc shaped gear of the desired tooth form having a width equal to the width of the finished gear. Supported on the slide *56* by means of brackets *94*, one on each side of the die roll *60*, are a pair of rollers *95*. The rollers are rotatably supported on pivot pins *94a*. The distance between the rollers is equal to the desired width of the finished gear. The supports may be arranged in such a manner that the center distance of the rollers may be varied to conform to different widths of gears. As the workpiece *W* and the die roll *60* rotate they cause the rollers *95* to be rotated by the contact friction, while the rollers prevent the plastic material of the workpiece from being squeezed out sideways and assure that both flanks of the gear teeth have smooth surfaces and that the finished gear teeth have the desired width. The illustration shown is intended merely to illustrate the principle, it being obvious that the specific arrangement for mounting of the rollers *95* may be varied and under conditions it may be desirable to provide these rollers with a positive power drive. Furthermore, the rollers may be adjustably supported from the stationary frame *20* of the machine.

Fig. 6 shows a modification of the die roll shown in Fig. 1. In Fig. 6 the die roll *96* is pro-

vided with circular flanges *97* of larger diameter than the die gear and these flanges are spaced apart a distance equal to the desired width of the teeth of the finished gear. The flanges confine the plastic metal during the rolling to prevent the formation of fins at the edges of the gear teeth.

The workpiece or blank *W* is held in the machine as will now be described. As shown in Fig. 4, a gear sector *98*, is pivotally supported on the frame *20* by a pivot pin *99*. The teeth of the sector *98* are arranged to engage corresponding teeth *100* which are cut into the surface of the cylinder *27*, parallel to its axis, so that upon oscillation of the gear sector *98*, the cylinder *27* and the shaft *24* are reciprocated axially toward and away from the shaft *21*. The gear sector *98* has a rearward extension *101* which is provided with a pin *102* for pivotal attachment of one link *103* of a toggle. The other link *104* of said toggle is pivotally attached to the link *103* by means of a pin *105*, while the other end of said link *104* is pivotally supported from the frame *20* by a stationary pivot *106*. The toggle formed by the links *103* and *104* is operated by means of a hydraulic cylinder *107* of suitable construction. The cylinder *107* is pivotally supported on a pin *108* mounted on a block *109*, which in turn is supported on the frame *20*. An adjustable piston rod *110* of the cylinder *107* is pivotally attached to the link *104* by means of a pin *111*. Thus by supplying compressed fluid alternately to opposite ends of the hydraulic cylinder *107*, the toggle is straightened out or collapsed, thereby rocking the gear sector *98* and reciprocating the shaft *24* as will be apparent. The operation of the hydraulic cylinder *107* may be controlled by means of a reversing valve of suitable construction. By providing the piston rod *110* with an adjusting nut *112* or other suitable means its length may be varied, thus enabling adjustment of the maximum clamping pressure exerted by the toggle on the workpiece *W*.

The machine may be provided with automatic means to remove the workpiece *W* from the jaws *32* and *37*, such means being illustrated in Figs. 4 and 5. In the construction shown therein the hub on the side of the workpiece *W* which engages the jaw *37* is much longer than the hub which engages the jaw *32*. Therefore, the friction between the former hub and the jaw *37* is greater and upon separation of the jaws *32* and *37*, the workpiece *W* follows the jaw *37* and is withdrawn from the jaw *32* until it abuts a stripper *113* which is attached to the cylinder *28* which forms a part of frame *20* of the machine. This stripper limits the lateral motion of the workpiece *W* so that it is pulled out of engagement with the jaw *37* and pin *38*, when the shaft *24* is withdrawn, whereupon the workpiece may be dropped into a suitable receptacle.

Fig. 5 also shows a further modification for maintaining the shafts *21* and *24* at a low temperature, so as to prevent overheating of the bearings and other parts of the machine which support said shafts. As the workpiece *W* is maintained at a high temperature during the rolling process, part of its heat is conducted away by the shafts *21* and *24* to other parts of the machine and this may cause serious overheating of the bearings and of said shafts with the result that the bearings are rapidly destroyed and the accuracy of the work of the machine suffers. Such difficulties are overcome in the following manner: The ends of the shafts

21 and 24 nearest to the workpiece W are surrounded by sleeves 114. The sleeve for shaft 21 is bolted to the frame 20 and that for shaft 24 is bolted to the piston 27. The outer ends of the respective sleeves 114 fit closely around the respective shafts 21 and 24, but the respective sleeves have enlarged bores throughout the major portion of their extent. Mounted inside of said bores near both ends thereof are packing rings 115 and 116. A circular space 117 is left between the packing rings and arrangements may be made whereby conduits supply a cooling fluid to pass through these circular spaces to thereby conduct heat away from the shaft and prevent such heat from passing to the bearings 22 and 25, respectively. As the shaft 24 and its supporting piston 27 are movable laterally it will of course be necessary to provide a flexible connection in the conduit for the circular space 117 of the sleeve surrounding the shaft 24. Such connection is not shown as its construction will be obvious to any one skilled in the art.

The cooling means for the shafts 21 and 24 just described further insure that the heat transmitted from the blank to the jaws 32 and 37 is quickly withdrawn, thereby also rapidly cooling the central part of the blank W so that only the rim of the blank is maintained in a plastic state whereas the hub is not deformed during the rolling operation of the gear teeth.

Fig. 2 shows an arrangement for heating the blank W during the forming of the teeth and for subsequent cooling thereof. Arranged about the axis of the shaft 21, and mounted on the stationary part of the machine are a suitable number of nozzles 118, which are supplied with a suitable heating fluid and which are arranged so that the flame thereof impinges upon the circumference of the blank W while the blank is rotating. The number of nozzles depends upon the diameter of the blank, the working temperature and the type of fuel used. The nozzles and the blank are preferably enclosed in a hood 119 to conserve heat and to prevent the free access of air which may cause oxidation and scaling of the workpiece during the rolling process. The hood is rigidly fastened to the machine frame and is provided with an opening 120 of sufficient size to permit the movement of the die 60 into and out of engagement with the blank W.

If desired the hood may be supplied through an additional nozzle 121 with a neutral gas which completely envelops the blank W so as to further prevent oxidation of the blank. After the die 60 has reached its innermost position so that the teeth on the blank W are fully formed, it may be desirable to discontinue the heating of the blank which may be accomplished either manually by the operation of suitable valves in the fuel supply for the nozzles 118, or the valves may be operated automatically in connection with the automatic control of the entire machine as will be explained hereinafter.

Under certain conditions it may further be desirable to cool the blank W after the forming process and before it is removed from the machine. This may be accomplished by supplying a cooling fluid through additional nozzles 122, or the supply of the cool neutral gas through the nozzle 121 may be increased so that a strong stream of such gas impinges upon the finished gear W to cool the same at a rapid rate.

The supply of cooling fluid may also be controlled by suitable control valves operated automatically as has been explained heretofore.

It will further be obvious that instead of using the gas heating means described other heating means may be employed such as induction heating, in which case the nozzle 118 would be replaced by a suitably shaped primary coil which induces secondary currents in the blank to heat the same. The method of heating a blank by induction is well known in the art. It is particularly suitable in the present case because it makes it possible to cause the heat developed in the blank to penetrate only so far in a radial direction that the rim is sufficiently plastic for ready formation of the teeth while the hub of the blank is relatively cool and rigid to avoid distortion thereof.

The electrical system for controlling the machine is illustrated in Figs. 7 and 8. Power is supplied from the lines L1 and L2, of a direct current power supply. The controller comprises double throw push button operated switches 200, 201, 202, 203. Each of these switches is provided with two normally open contacts 200a, 201a, 202a, 203a, and 200b, 201b, 202b, and 203b, respectively, so arranged that either one or the other of the contacts of the respective switch may be closed. There are also provided five normally open starting push button switches 204, 205, 206, 207, and 208, respectively, and three normally closed stopping push button switches 209, 210, 211, and 212. The main motor 53 comprises an armature 53a, and a shunt field winding 53b, the latter being controlled by a rheostat 53c. The armature 53a is controlled by a pair of electromagnetic reversing switches 213 and 214, respectively. The forward switch 213 is provided with an energizing coil 213a, normally open main contacts 213b and 213c, and normally closed auxiliary contacts 213e and normally open auxiliary contacts 213f. The reverse switch 214 is provided with an energizing winding 214a, normally open main contacts 214b and 214c, normally closed auxiliary contacts 214e and normally open auxiliary contacts 214f. The terminals of the motor armature 53a, are connected in the conventional manner to the main contacts of the switches 213 and 214, so that upon alternate energization of the two switches the motor is connected to rotate in the forward or reverse direction, respectively. The feed motor 64 is controlled by an electromagnetic switch 215, having an energizing winding 215a, and normally open main contacts 215b and 215c, by means of which the feed motor armature 64a may be connected to the lines L1 and L2, when the switch 215 is energized. The switch 215 is further provided with normally open auxiliary contacts 215e and normally closed auxiliary contacts 215f and 215g. The return motor 65 is controlled by an electromagnetic switch 216, which is provided with an energizing winding 216a, and normally open main contacts 216b and 216c, for connecting the motor armature 65a to the lines L1, and L2, when the switch 216 is energized. Switch 216 is also provided with a normally closed auxiliary contact 216e and normally open auxiliary contacts 216f and 216g. Connected between one of the main contacts of the switch 213 and one terminal of the motor armature 53a is the energizing winding 217a, of an overload relay 217, which is provided with normally closed contacts 217b. Mounted adjacent to the slide 56, which is illustrated in the diagram as a reciprocating bar, and as shown in full lines in its extreme outer position, are the normally closed limit switches 218a, 219a, 220a, and the normally open limit switches 221a, 222a, and 223a, while

suitable abutments 218b to 223b are provided on the slide 56 for operating the corresponding limit switches. Mounted adjacent to the gear sector 98 is a normally open limit switch 229, which is closed when the toggle is straightened out. There is also provided a timing relay 230 having an energizing coil 230a, normally open contacts 230b, and a retarding dash-pot 230c. Mounted on or otherwise coupled to the rotating shaft 70 is a switch 231 having an arm 231a, which is adapted to bridge stationary contacts 231b and 231c, as the arm is rotated by the shaft.

To control the fuel or other heating medium the system is provided with actuating solenoids 232 which admit heating energy when energized. An indicating lamp 233 is connected in parallel with the solenoids to indicate when they are energized. The solenoids in turn are controlled by a relay 234, which has an energizing winding 234a, and normally open contacts 234b, 234c, and 234d. The switches 213 and 214, are alternately energized by a reversing relay 235, which is provided with an energizing winding 235a, a contact lever 235b, and stationary contacts 235c and 235d. When the coil 235a is energized it causes the lever 235b to move from one stationary contact to the other to make circuit therewith. A manually operated reversing valve 236 is provided for controlling the supply of working fluid under pressure to the hydraulic cylinder 107. A pressure regulating valve of any suitable type (not shown) may be inserted in the fluid supply conduit to regulate the pressure of the fluid and thus the thrust applied to the shaft 24.

When it is desired to roll a gear the operator sets the switches 200, 201, 202 and 203 for automatic operation which closes the contacts 200b, 201b, 202b, 203b. Thereupon he actuates the hydraulic valve 236 which admits fluid pressure to the cylinder 107 to straighten out the toggle 103-104 and clamp the gear blank W in the machine as has been described heretofore. As the toggle straightens out the gear sector 98 closes the limit switch 229 to connect the bus bar 237, to the line L2. This establishes a circuit from bus bar 237, through contacts 200b, limit switch 221a, energizing coil 234a, limit switch 218a, to line L1, thereby actuating the relay 234 to close the contact 234b. A circuit is thus established from line L2, through the coils 232 and the pilot light 233, through contacts 234b, to line L1, and the coils 232 are energized to admit fuel to the gas burner nozzles 118. It should be mentioned here that the gas valves may be provided with auxiliary means (not shown), which during the idle periods furnish a limited supply of fuel, so as to keep the burned ignited. Any other arrangement serving the same purpose may be made, such as an ignition coil which is energized in parallel with the coils 232 so as to ignite the gas flame upon opening of the gas valves.

Energization of relay 234 also closes the auxiliary contacts 234d, which are in parallel with the limit switch 221a, the latter being closed in the extreme outward position of the slide block 56, so that the relay 234 remains energized when the limit switch 221a is opened upon the slide traveling inwardly. When the slide reaches its innermost position the limit switch 218a is opened thereupon again deenergizing the relay 234 and cutting off the heating supply.

With the bus bar 237 energized, a circuit is also established from bus bar 237 to contacts 201b, contacts 214c, energizing coil 213a, through contacts 235d, switch lever 235b, to line L1, or

alternately through contact 213e, energizing coil 214a, contact 235c, switch lever 235b, to line L1. Thus the forward switch 213 or alternately the reverse switch 214 are energized, depending upon the position of the lever 235b. In the position shown the forward switch 213 is energized and it closes its normally open main contacts 213b and 213c and connects the motor 53 for right hand rotation of the machine. Rotation of the machine causes rotation of the switch arm 231a and this periodically establishes a circuit from line L2, through the switch 231, energizing coil 235a, to line L1. Each energization of the electromagnet 235a causes the switch arm 235b to oscillate from one to the other stationary contacts 235c or 235d, to alternately energize the reversing switches 213 and 214. When the reverse switch 214 is energized its main contacts connect the motor 53 to the line for reverse rotation, and the rotation of the motor 53 alternates as long as the switch 231 rotates.

A circuit is also established from bus bar 237, through contacts 202b, limit switch 219a, energizing coil 215a, over contacts 217b and 216e, to line L1. This energizes the feed motor switch 215 and connects the feed motor 64 to the bus bars L1 and L2, by closure of the main contacts 215b and 215c. The feed motor thus moves the slide 56 inwardly to feed the die roll into the gear blank to generate the gear teeth. When the slide 56 has reached its innermost position it opens the limit switch 219a, thereby deenergizing the winding 215a, and the switch 215 disconnects the feed motor 64 from the line and the slide comes to a standstill.

Just prior to the moment when the slide reaches the innermost position the limit switch 222a closes, while deenergization of switch 215 closes the auxiliary contacts 215f, so that upon stoppage of the slide 56 by disconnection of the motor 64, a circuit is established from the bus bar 237, through contacts 202b, limit switch 222a, energizing coil 230a, over contacts 215f to line L1. This energizes the timing relay 230, while the slide 56 stands still. During this time the motor 53 continues to rotate the gear and the die roll in one direction or another, dependent upon the position of the switch 235, so that the tool, being in contact with the finished gear, burnishes the teeth thereof to give it a high surface finish.

After a lapse of time determined by the adjustment of the dash-pot 230c, the relay 230 closes its normally open contacts 230b. This establishes a circuit from the bus bar 237, through contacts 203b, 230b, limit switches 223a, and 220a, energizing coil 216a, and contacts 216g to line L1, to energize the return motor solenoid switch 216, which upon response closes its main contacts to connect the return motor armature 65a to the lines L1 and L2, and also energize the brake 93 to release the same. Upon response the relay 216 also closes its auxiliary contacts 216f and opens the auxiliary contacts 216e. Opening of the auxiliary contacts 216e prevents the feed motor switch 215 from being energized upon re-closure of limit switch 219a on the return stroke of the slide 56. Closure of auxiliary contacts 216f bypasses the contacts 230b, 223a, so that upon deenergization of the time relay 230 and reopening of the limit switch 223a on the return movement of the slide 56, the solenoid switch 216 and the return motor 65 remain energized until the slide 56 has returned to its outermost position, in which position the normally closed limit switch 220a is opened to deenergize the switch

216 and stop the return motor 65. When the slide 56 has again reached the outermost position, the operator may reverse the pressure fluid to the cylinder 107 which acts to move the gear sector 98 to release the gear from the holding jaws and opens the limit switch 229 to deenergize the bus bar 237, so as to cut off energy from all of the solenoid switches to bring the equipment to rest.

If it is desired to adjust the valve solenoids 232, the operator may operate switch 200 to open the contacts 200b and close the contacts 200a. He is then able, by closure of the push button switch 204, to energize the relay 234 by a circuit from line L2, over contacts 200a, 204, 209, through energizing coil 234a, and limit switch 218a to line L1. The push button 204 is paralleled by the contacts 234c, so that the coil 234a remains energized when the push button 204 is released. If it is desired to deenergize the relay 234, the push button 209 may be depressed which opens the maintaining circuit of the relay coil 234a.

If it is desired to control the motor 53 manually for rotating the gear and the gear blank independent of the other functions of the machine, the control switch 201 is operated to open the contacts 201b and close the contacts 201a. Thereupon the manual push button switch 205 may be depressed which establishes a circuit from line L2, through contacts 201a, 205, 210, 214e, coil 213a, or alternately contacts 213e and coil 214a, through the circuit already traced, to energize either the switches 213 or 214 for connecting the motor 53 to the lines L1, and L2. When the motor 53 rotates the machine it also rotates the switch 231 to actuate the reverser 235 in the manner afore-described. While the slide stands still, the switch 231 is not operating and therefore motor 53 will always operate in the same direction when energized. If under these conditions it is desired to reverse rotation of the motor 53, the operator actuates the push button switch 206 which energizes the coil 235a to commutate the switch 235 and the connections of motor 53 are reversed. It is also to be noted that operation of the motor 53 ceases upon opening of switch 210.

If it is desired to move the slide 56 independently in one direction or the other, the switch 202 is operated to open the contacts 202b, and close the contacts 202a, and also the switch 203 is operated to open the contacts 203b and close the contacts 203a. If then the operator wishes to feed the slide 56 inwardly, he pushes the button 207, thereby establishing a circuit from line L2, through contacts 202a, 207, 211, limit switch 219a, through the energizing coil 215a and over the circuit already traced. This energizes the switch 215 to connect the said motor 64 to the line to move the slide inwardly. Response of switch 215 closes the auxiliary contact 215e, which parallels the switch 207, so that the feed motor continues to operate upon release of the push button 207, until in the innermost position the limit switch 219a, opens to disconnect the feed motor from the line. If the operator wishes to stop the slide 56 before it reaches the innermost position he may push the push button switch 211, thereby deenergizing the switch 215 which opens the maintaining contact 215e and the feed motor comes to rest. If the operator wishes to actuate the return motor he pushes the button 208. This closes a circuit from line L2, through contacts 203a, 208, 212, limit switch contact 220, through the coil 216a, contact 215g, to line L1. Thus the switch

216 is energized to energize the return motor 65. Energization of relay 216 also closes contacts 216g to maintain the switch 216 energized upon release of the push button 208, and until the limit switch 5 220a opens the circuit upon the slide 56 returning to the retracted position. If in any other position the operator wishes to stop the return movement of the slide 56, he pushes the push button 212, which momentarily deenergizes the switch 216 and stops the equipment.

It will thus be seen that the system provides for independent manual control of each individual movement of the machine and for full automatic control to operate the machine through 15 a complete cycle of forming a gear. The control system described herein has been chosen by way of example. It may be modified in many ways without departing from the invention as will be obvious to one skilled in the art.

20 It will of course be understood that suitable automatic accelerating means may be used in the armature circuits of the motors 53, 64, and 65, where the size of the motor requires separate 25 means to limit the inrush current upon energization of the motor armature. It will further be apparent that the speed of the different motors may be adjusted by adjusting their field regulating resistors and it is further possible to provide 30 separate field regulators for the field winding 53b of the motor 53, so that the field regulators for the forward and reverse direction may be adjusted separately and the motor may be operated at different speeds in the two directions. 35 Where desirable induction motors or any other suitable type of motors may be employed for the machine, as is obvious to one skilled in the art.

What I claim as new and desire to secure by Letters Patent is:

40 1. In an automatic gear rolling machine, in combination, a base, two shafts rotatably mounted in axial alignment on said base and provided at their adjacent ends with cooperating jaws for clamping a workpiece therebetween, 45 means including fluid pressure means arranged for axially moving one of said shafts relative to the other, a slide supported on said base for reciprocation perpendicular to the axis of said shafts, an arbor rotatably mounted on said slide 50 in parallel with said shafts and adapted to receive a toothed die, a drive shaft mounted on said base parallel to the direction of motion of said slide, a reversible motor, fixed speed ratio driving connections between said motor, said drive shaft, said arbor, and the other of said first 55 mentioned shafts, a planetary gear set supported on said base and comprising a reversible output shaft connected to said slide to move it in opposite directions, an input shaft, and a rotatable casing geared to said output shaft, a feed motor connected to said input shaft to effect rotation of said casing in one direction and a return motor connected to said casing to effect rotation thereof in the opposite direction, automatic means responsive to operation of said hydraulic means for controlling energization of said motors, including automatic means for periodically reversing the energization of said reversible motor, automatic means responsive to the position of said slide to control said automatic reversing means and to alternately energize said feed motor and said return motor and including time delay means arranged to delay the energization of said return motor, and manually operated selector means to provide for individual manual energization of

13

said motors independent of the operation of said hydraulic means.

2. In an automatic gear rolling machine, in combination, a base, two shafts rotatably mounted in axial alignment on said base and provided at their adjacent ends with cooperating jaws for clamping a workpiece therebetween, means including fluid pressure means arranged for axially moving one of said shafts relative to the other, a slide supported on said base for reciprocation perpendicular to the axis of said shafts, an arbor rotatably mounted on said slide in parallel with said shafts and adapted to receive a toothed die, a drive shaft mounted on said base parallel to the direction of motion of said slide, a reversible motor, fixed speed ratio driving connections between said motor, said drive shaft, said arbor, and the other of said first mentioned shafts, a planetary gear set supported on said base and comprising a reversible output shaft connected to said slide to move it in opposite directions, an input shaft, and a rotatable casing geared to said output shaft, a feed motor connected to said input shaft to effect rotation of said casing in one direction and a return motor connected to said casing to effect rotation thereof in the opposite direction, automatic means responsive to operation of said hydraulic means for controlling energization of said motors, including automatic means for periodically reversing the energization of said reversible motor, automatic means responsive to the position of said slide to control said automatic reversing means and to alternately energize said feed motor and said return motor, and manually operated selector means to provide for individual manual energization of said motors independent of the operation of said hydraulic means.

3. In an automatic gear rolling machine, in combination, a base, two shafts rotatably mounted in axial alignment on said base and provided at their adjacent ends with cooperating jaws for clamping a workpiece therebetween, means including fluid pressure means arranged for axially moving one of said shafts relative to the other, a slide supported on said base for reciprocation perpendicular to the axis of said shafts, an arbor rotatably mounted on said slide in parallel with said shafts and adapted to receive a toothed die, a drive shaft mounted on said base parallel to the direction of motion of said slide, a reversible motor, fixed speed ratio driving connections between said motor, said drive shaft, said arbor, and the other of said first mentioned shafts, a planetary gear set supported on said base and comprising a reversible output shaft connected to said slide to move it in opposite directions, an input shaft, and a rotatable casing geared to said output shaft, a feed motor connected to said input shaft to effect rotation of said casing in one direction and a return motor connected to said casing to effect rotation thereof in the opposite direction, automatic means responsive to operation of said hydraulic means for controlling energization of said motors, including automatic means for periodically reversing the energization of said reversible motor, and automatic means responsive to the position of said slide to control said automatic reversing means and to alternately energize said feed motor and said return motor.

4. In a gear rolling machine, a reciprocable slide, a die support rotatably mounted on said slide with its axis transversely to the movement of said slide, a work holder including two axially aligned rotatable work supporting shafts having

14

clamping means at their adjacent ends, reversible actuating means connected to one of said shafts for axially moving the same relative to the other and clamping a workpiece into driving engagement with said clamping means, a reversible motor connected to said other shaft and to said die support for rotating said other shaft and said die support at fixed speed ratios relative to each other, a planetary gear set having a rotatable casing connected to said slide for moving the same transversely in opposite directions in accordance with the direction of rotation of said casing, a motor connected to an input shaft of said differential and adapted when energized to rotate said casing to move said slide and said die support toward said work holder, a second motor connected to another input shaft of said planetary gear set and adapted to rotate said casing in the opposite direction, for moving said slide away from said work holder, means for heating said workpiece in situ, and adjustable means for selectively effecting operation of any of said motors and of said heating means in accordance with a predetermined adjustable cycle.

5. In a gear rolling machine, a reciprocable slide, a die support rotatably mounted on said slide with its axis transversely to the movement of said slide, a work holder including two axially aligned rotatable work supporting shafts having clamping means at their adjacent ends, reversible means connected to one of said shafts for axially moving the same relative to the other and clamping a workpiece into driving engagement with said clamping means and to regulate the clamping pressure, a reversible motor connected to said other shaft and to said die support for rotating said other shaft and said die support at fixed speed ratios relative to each other, a planetary gear set having a rotatable casing connected to said slide for moving the same transversely in opposite directions in accordance with the direction of rotation of said casing, a motor connected to an input shaft of said planetary gear set and adapted when energized to rotate said housing to move said slide and said die support toward said work holder, a second motor connected to another input shaft of said planetary gear set and adapted to rotate said casing in the opposite direction, for moving said slide away from said blank, means for heating said workpiece in situ, and adjustable means for selectively effecting operation of any of said motors and of said heating means in accordance with a predetermined adjustable cycle.

6. In an automatic gear rolling machine, in combination, a base, two shafts rotatably mounted in axial alignment on said base and provided at their adjacent ends with cooperating jaws for clamping a workpiece therebetween, means including fluid pressure means arranged for axially moving one of said shafts relative to the other, a slide supported on said base for reciprocation perpendicular to the axis of said shafts, an arbor rotatably mounted on said slide in parallel with said shafts and adapted to receive a toothed die, a chamber surrounding each of said shafts in proximity of its respective jaw, a chamber surrounding said arbor adjacent to its die receiving end, said chambers being adapted to receive a cooling fluid for cooling said shafts and said arbor, a drive shaft mounted on said base parallel to the direction of motion of said slide, fixed speed ratio driving connections between said drive shaft, said arbor, and the other of said first mentioned shafts, a planetary gear set supported

on said base and comprising an input shaft, a reversible rotatable casing and a reversible output shaft connected to said slide to move it in one direction upon rotation of said input shaft, and in the other direction upon rotation of said casing while said input shaft is at rest.

7. In an automatic gear rolling machine, in combination, a base, two shafts rotatably mounted in axial alignment on said base and provided at their adjacent ends with cooperating jaws for clamping a workpiece therebetween, means including fluid pressure means arranged for axially moving one of said shafts relative to the other, a slide supported on said base for reciprocation perpendicular to the axis of said shafts, and provided with a screw thread, an arbor rotatably mounted on said slide in parallel with said shafts and adapted to receive a toothed die, a drive shaft mounted on said base parallel to the direction of motion of said slide, a reversible motor, fixed speed ratio driving connections between said motor, said drive shaft, said arbor, and the other of said first mentioned shafts, a planetary gear set supported on said base and comprising a reversible output shaft provided with a threaded end engaging said screw thread of said slide to move it in opposite directions, an input shaft, and a rotatable casing geared to said output shaft, a feed motor connected to said input shaft to effect rotation of said casing in one direction and a return motor connected to said casing to effect rotation thereof in opposite directions, automatic means responsive to operation of said hydraulic means for controlling energization of said motors, including automatic means for periodically reversing the energization of said reversible motor, and automatic means responsive to the position of said slide to control said automatic reversing means and to alternately energize said feed motor and said return motor.

8. In an automatic gear rolling machine, in combination, a base, two shafts rotatably mounted in axial alignment on said base and provided at their adjacent ends with cooperating jaws for clamping a workpiece therebetween, means including fluid pressure means arranged for axially moving one of said shafts relative to the other, a slide supported on said base for reciprocation perpendicular to the axis of said shafts, and provided with a screw thread, an arbor rotatably mounted on said slide in parallel with said shafts and adapted to receive a toothed die, a drive shaft mounted on said base parallel to the direction of motion of said slide, a reversible motor, fixed speed ratio driving connections between said motor, said drive shaft, said arbor and the other of said first mentioned shafts, a planetary gear set supported on said base and comprising a reversible output shaft provided with a threaded end engaging said screw thread of said slide to move it in opposite directions, the axis of said output shafts, said arbor, and said first named two shafts being in a common plane, an input shaft, and a rotatable casing geared to said output shaft, a feed motor connected to said input shaft to effect rotation of said casing in one direction and a return motor connected to said casing to effect rotation thereof in the opposite direction, automatic means responsive to operation of said hydraulic means for controlling energization of said motors, including automatic means for periodically reversing the energization of said reversible motor, and automatic means responsive to the position of said slide to control said automatic reversing means and to alter-

nately energize said feed motor and said return motor.

9. In an automatic gear rolling machine, in combination, a base, two shafts rotatably mounted in axial alignment on said base and provided at their adjacent ends with cooperating jaws for clamping a workpiece therebetween, means including fluid pressure means arranged for axially moving one of said shafts relative to the other, 5 a slide supported on said base for reciprocation perpendicular to the axis of said shafts, and provided with a screw thread, an arbor rotatably mounted on said slide in parallel with said shafts and adapted to receive a toothed die, a drive shaft mounted on said base parallel to the direction of motion of said slide, a reversible motor, fixed speed ratio driving connections between said motor, said drive shaft, said arbor, and the other of said first mentioned shafts, a planetary gear set supported on said base and comprising a reversible output shaft provided with a threaded end engaging said screw thread of said slide to move it in opposite directions, an input shaft, and a rotatable casing geared to said output shaft, a thrust bearing concentric with said output shaft and arranged to receive the reaction of the forces exerted upon said slide to move it in opposite directions, a feed motor connected to said input shaft to effect rotation of said casing in 20 one direction and a return motor connected to said casing to effect rotation thereof in the opposite direction, automatic means responsive to operation of said hydraulic means for controlling energization of said motors, including automatic means for periodically reversing the energization of said reversible motor, and automatic means responsive to the position of said slide to control said automatic reversing means and to alternately energize said feed motor and said return motor.
10. In an automatic gear rolling machine, in combination, a base, a shaft rotatably mounted on said base, hydraulic means for moving a workpiece into driving engagement with said shaft, a slide supported on said base for reciprocation perpendicular to the axis of said shaft, an arbor rotatably mounted on said slide in parallel with said shaft and adapted to receive a toothed die, a reversible motor, fixed speed ratio driving connections between said motor, said arbor, and said first mentioned shaft, a planetary gear set supported on said base and comprising a reversible output shaft connected to said slide to move it in opposite directions, an input shaft, and a rotatable casing geared to said output shaft, a feed motor connected to said input shaft to effect rotation of said casing in one direction and a return motor connected to said casing to effect rotation thereof in the opposite direction, automatic means responsive to operation of said hydraulic means for controlling energization of said motors, including automatic means for periodically reversing the energization of said reversible motor, and automatic means responsive to the position of said slide to control said automatic reversing means and to alternately energize said feed motor and said return motor.
11. In an automatic gear rolling machine, the combination in accordance with claim 10, with means for heating the workpiece in situ, automatic control means responsive to operation of said hydraulic means and said feed motor energizing means for operating said heating means,

and manual selector means to provide for alternate manual control of said heating means in addition to said hydraulic means and said feed motor energizing control means.

12. In a gear rolling machine of the character described, manually controlled hydraulic means for selectively clamping and releasing a gear blank, electromagnetic means responsive to the clamping action of said hydraulic means and including cycling means for successively effecting, initiation of heating the gear blank, rotating the gear blank and tool alternately in opposite directions, feeding the tool into the work, terminating the heating and the feeding of the tool after a given travel of the latter, terminating rotation of the blank and tool and withdrawing the latter to its initial position, and manual means for

5

10

selectively rendering response of said electromagnetic means to said clamping action and said cycling means effective and alternatively rendering said electromagnetic means effective to afford at will individual operation of any of the aforementioned operations, including rotation of said blank and said tool in either direction.
